UNITED STATES PATENT OFFICE

2,512,943

ADAPTABLE BRACE

Harland S. Jones, Union, N. Y.

Application March 28, 1949, Serial No. 83,792

1 Claim. (Cl. 77—43)

1

This invention comprises novel and useful improvements in an adaptable brace and more specifically pertains to an adjustable and adaptable brace which is capable of assemblage into a variety of tools for rotating bits in accordance with various working conditions.

It is a primary object of this invention to provide a brace which is capable of assembling into various types of braces for rotating bits in improved manners, in confined quarters, with increased leverage, and wherein the conversion of the tool may be effected with ease and at little expense.

Important features of the invention reside in the provision of a sectional brace provided with a conventional bit chuck to whose splined neck portion may be detachably connected a reversible ratchet clutch, for detachably receiving a conventional brace handle or a ratchet handle whereby the tool may be selectively used for fast drilling or boring in relatively open quarters, or may be employed with great leverage in cramped quarters.

A further feature of the invention resides in the novel and improved attaching means for connecting a brace handle or a ratchet handle to the ratchet clutch, to effect this attachment with ease and certainty and to facilitate the removal of the handle when the same is to be changed.

A still further feature of the invention resides in the provision of a novel and improved manner of securing by means of an adaptor sleeve, fastened to an extension upon the end of the splined neck of the chuck, an anti-friction bearing handle, and wherein the adaptor sleeve may be employed for securing the chuck, after the ratchet clutch has been removed therefrom, to a power tool for use therewith.

These, together with various ancillary features and objects of the invention, which will later become apparent as the following description proceeds, are attained by this device, a preferred embodiment of which has been illustrated by way of example only in the accompanying drawings, wherein:

Figure 1 is a side elevational view, parts being broken away, showing the device assembled as a ratchet operated brace;

Figure 2 is a fragmentary side elevational view of the arrangement shown in Figure 1, parts being broken away and parts shown in section to illustrate the construction of the detachable handle fastening means of the device;

Figure 3 is a sectional detailed view taken substantially in the plane of the horizontal section line 3—3 of Figure 1;

Figure 4 is a side elevational view of the device showing the chuck handle means secured thereon, and the ratchet handle removed therefrom; and,

2

Figure 5 is an exploded elevational view illustrating the arrangement and construction of the various elements of the assemblage shown in Figure 4.

5 Referring now more specifically to the accompanying drawings, wherein like numerals designate similar parts throughout the various views, attention is directed first to Figure 1 wherein a suitable arrangement of the elements of the invention are illustrated providing a brace having a ratchet handle whereby great leverage may be imparted for rotating the chuck, wherein the chuck may be reversibly rotated, and wherein partial rotation of the chuck may be readily effected in either direction, and wherein the tool is especially adapted for use in cramped quarters. 10 In this arrangement there is illustrated a bit chuck 10 of suitable and known design, for holding a tool bit 12 of any desired type, which chuck in itself forms no part of this invention. However, as shown best in Figure 5, the chuck is provided with a neck portion 14 which is provided with longitudinal splines 16, and a shoulder 18 thereon for receiving a spacer washer or collar 20 and a reversible ratchet clutch indicated generally at 22. This clutch is in itself of known design, and is provided with the customary annular reversing sleeve 24 for reversing the clutch gripping action upon the splined portion 16. The 15 ratchet clutch 22 is secured upon the splined portion 16 of the neck 14 as by means of a castellated nut 26 screwed upon the threaded portion 28 of the neck, and which nut is retained in locked position as by a cotter pin 30 which may be inserted between appropriate castellations 32 of the nut and through a cotter pin diametrical aperture 34 appropriately positioned in an extension 36 on the neck 14. The outer end of this extension is provided with a conical recess indicated in dotted line at 38 in Figures 4 and 5.

20 As shown in Figures 1, 2 and 5, the ratchet clutch assembly 22 is formed with a laterally extending shank portion 40, carrying the above mentioned reversing sleeve 24, and also receiving in any suitable detachable manner, or if desired as an integral extension thereof, a shank extension 42 which is provided with an annular shoulder or flange 44 and with a tapering or conical outer end 46. As shown in Figure 2, the flange 44 is further provided with outwardly projecting guide pins 48 for a purpose to be later set forth.

25 A ratchet handle 50 is provided with a diametrically enlarged extremity 52 whose outer end is externally threaded as at 54, and whose outer surface is provided with recesses or sockets 56 for detachably but non-rotatively receiving the guide pins 48 therein, when the end is pressed upon the shank 42. As further shown in Figure 2, the enlarged portion 52 is provided with a 30 tapered bore 58 for frictionally receiving the ta-

pered extremity 46 of the shank. A coupling gland 60 having an internally threaded surface for engagement with the threaded portion 54 is rotatably received above the shank extension 42 to establish a quickly engageable and detachable coupling for rigidly securing the handle 62 to the shank 42. It should be here noted that when the coupling gland is tightened upon the enlarged portion 52, the guide pins 48 are forced into the recesses 56, while the tapered extremity 46 of the shank is frictionally engaged in the correspondingly tapered recess 58, to rigidly and firmly secure the handle to the shank. When it is desired to remove the handle, the mere reverse rotation of the gland 60 will cause the same to move backwardly on the threaded portion 54, until the end of the gland engages the end of the reversing sleeve 24, whereby continued reverse movement of the coupling gland serves to force the enlarged portion 52 of the handle upwardly and away from its frictional engagement with the guide pins 48 and the tapering extension or extremity 46 of the shank.

As will be readily understood, a similar connection may be employed for securing a conventional brace handle to the shank 42, to thereby adapt the device for use as a conventional speed brace with a crank handle or as a ratchet handle actuated brace. In its latter operation, any suitable means may be employed for applying pressure to the end of the extension 36, to thereby force the bit into the work, as when exceptionally hard wood is being drilled or bored by a drill bit or wood bit, as when drilling holes in metal, in employing the device in cramped quarters such as between studs or joints, as by plumbers or electricians, and similar uses.

Referring now again to Figures 4 and 5, it will be seen that a handle may be rotatably secured to the extension of the chuck member. This handle obviously may be employed with the ratchet handle 50, to provide an easy means for applying pressure by the other hand of the operator.

This handle includes a suitable knob or head 62 which has a preferably integral depending tubular bushing 64 extending axially therefrom. Suitable set screws 66 extend through the sides of the bushing 64 for co-action with an adaptor sleeve to be now described.

This adaptor sleeve comprises a sleeve portion 68 provided with a suitable bore 70 at front extending from one end thereof for detachable engagement upon the extension 36, upon which the sleeve may be secured as by a fastening or shear pin 72 extending through aligned diametrical aperture 74 in the sleeve 68, and also through a diametrical bore 76 in the extension 36. At its closed end, the sleeve 68 is provided with a diametrically reduced extension 78 which terminates in a conical point 80. The extension 78 is of sufficient diameter to snugly receive the bushing 64, which may be secured thereon by means of the set screw 66 above mentioned, whereby the handle may thus be employed to rotate the neck 14 and the chuck 10.

As further shown in Figure 5, the extension 78 joins the sleeve 68 with a horizontal shoulder which is perpendicular to the axis of the adaptor sleeve, and an anti-friction bearing assembly 82 of any conventional design is formed upon this shoulder.

The operation and utility of the construction indicated in Figures 4 and 5 is as follows. With the part indicated at Figure 5 assembled in the manner shown in Figure 4, the reversible ratchet brace sleeve 24 may be properly adjusted, to permit rotation of the clutch of the chuck 10 in a desired direction, whereupon the clutch element 22 may serve as a handle or hand grip for positioning the tool. Upon rotation by hand of the head or handle 62, the engagement of the bushing 64 with the extension 78, and the engagement of sleeve 68 with extension 36 will serve to rotate the chuck head manually for certain uses such as reaming bores, and in some instances operating bits. However, the bushing 64 and handle 62 may be removed, and the extension 78 engaged in the chuck socket of any suitable power tool whereby the bit may be power operated.

Alternatively, the conical tip 80 may be engaged by any suitable jig for positioning the device, the ratchet handle 50 may be attached, and the brace operated as a ratchet brace. Finally, the adaptor sleeve 68 and handle 62 may be removed, and a suitable implement engaged in the conical recess 38 to apply pressure to the chuck while the ratchet handle is operated for boring or drilling.

From the foregoing, the various manners of assembling and employing the tool, and the obvious manifold advantages and uses of each particular assemblage of the elements of the device will be readily understood and further explanation is believed to be unnecessary. It is, however, to be distinctly understood that the invention and the principles thereof are not to be limited by the exact construction shown and described, except as required by the scope of the appended claim.

Having described the invention, what is claimed as new is:

A sectional brace comprising a chuck, a splined neck on said chuck, a reversible ratchet clutch detachably received on said neck, an extension non-rotatably secured to said neck and extending through and beyond said ratchet clutch, a head mounted on said extension, a handle for said ratchet clutch and fastening means rotatably connecting said handle and said ratchet clutch, said head including an adaptor sleeve rotatably attached thereto and engageable upon said extension and having a diametrically reduced end, an anti-friction bearing assembly on said adaptor sleeve, a bushing on said head embracing said reduced end and journaled on said bearing assembly, a shear pin non-rotatably but yieldably connecting said sleeve to said extension, means selectively locking said head to said adapter sleeve.
